[57] CLAIM

The ornamental design of a fixed pitch propeller for aircraft, substantially as shown.

DESCRIPTION

FIG. 1 is a perspective view of a fixed pitch propeller for aircraft showing my design;

FIG. 2 is a rear elevation thereof;

FIG. 3 is a front elevation thereof;

FIG. 4 is a side elevation thereof;

FIG. 5 is an enlarged vertical fragmentary section through the central portion thereof looking generally along the line 5—5 of FIG. 3; and

FIG. 6 is a transverse section looking generally along the line 6—6 of FIG. 3.
